UNITED STATES PATENT OFFICE.

JOHN B. MARTIN, OF CINCINNATI, OHIO.

BED-SPRING.

1,172,154.

Specification of Letters Patent. Patented Feb. 15, 1916.

Application filed December 3, 1914. Serial No. 875,287.

To all whom it may concern:

Be it known that I, JOHN B. MARTIN, a citizen of the United States, residing at Cincinnati, in the county of Hamilton and State 5 of Ohio, have invented certain new and useful Improvements in Bed-Springs; and I do declare the following to be a full, clear, and exact description of the invention, such as will enable others skilled in the art to 10 which it appertains to make and use the same.

This invention relates to improvements in bed springs.

The main object of the invention is to 15 provide a spring of this character so constructed as to stiffen the outer edges of the bed and prevent the user from accidentally rolling or slipping off when asleep.

Another object is to provide a spring of 20 this character with means for reliably retaining a mattress thereon and holding it against slipping sidewise.

With these and other objects in view, the 25 invention consists of certain novel features of construction, and the combination and arrangement of parts as will be more fully described and claimed.

In the accompanying drawings: Figure 1 30 represents a plan view of a portion of a woven wire bed spring equipped with this improvement; Fig. 2 represents a side elevation thereof; Fig. 3 is an enlarge detail cross sectional view; Fig. 4 is a detail perspective view of one of the reinforcing or 35 bracing springs; Fig. 5 is a top plan view of a portion of another form of spring provided with this improvement; Fig. 6 is a side elevation thereof; and Fig. 7 is a transverse section taken on the line 7—7 of Fig. 5.

In the embodiment illustrated in Figs. 1 40 to 4 the invention is shown applied to a woven wire bed spring S of ordinary construction and said invention comprises a plurality of truncated cone shaped spiral springs 1 arranged in longitudinal alignment along the opposite side edges of the woven wire spring S between the edges of the wire fabric F and supporting side bars 2 and 3 arranged below and spaced from 45 said fabric as is shown clearly in Figs. 1 and 2, said bars being here shown composed of angle iron and having upstanding connecting ends E to the upper edges of which are secured spiral springs 8 which connect said 50 ends with a fabric F and whereby a housing 55 for the springs 1 is formed.

The springs 1 are arranged alternately with the base of one extending upwardly and that of the next downwardly as shown in Fig. 2 to adapt them to be arranged in 60 close proximity and a greater number to be employed than could be if otherwise arranged thus stiffening the edges. Any suitable means may be employed for attaching these springs to the fabric F and the supporting bars 2 and 3, a wire of the fabric at each side edge thereof being shown connected by loops L with the upper ends of the springs 1 for connecting them to the fabric 65 and to each other (see Fig. 2). The alternating springs 1 which have their bases projecting upwardly to engage with the wire fabric F are provided with mattress stops 4 here shown in the form of a loop projecting upwardly from the final coil at the base 70 of said spring on one side thereof and which is designed to engage the side edges of the mattress M when the springs are in operative position and hold said mattress M 75 against sidewise movement as is clearly 80 shown in Fig. 2.

In Figs. 5, 6 and 7 the invention is shown applied to a bed spring constructed of slats 5 with spiral springs 6 mounted between them such as is common in bed springs of 85 this character, the said springs 6 being shown connected by the usual chains 7. Arranged between the spiral springs 6 on the side edges of the bed spring are truncated 90 cone shaped spiral springs 1' constructed 95 similarly to those above described and having their bases projecting upwardly and the final coils thereof provided with upwardly projecting loops 4' to form stops for the mattress. These springs 1' are connected 95 with the adjacent springs 6 by chains 7'. These reinforcing springs which are disposed at the side edges of the bed spring are compressible uniformly and tend to reinforce said spring at these edges and offer 100 greater resistance to the weight of the user than the woven wire fabric or the springs 6 from which the spring is ordinarily constructed. If desired, these springs 1 and 1' 105 may be made of heavy wire so that they will not readily yield to pressure and thus will hold the side edges of the bed normally flush with the body portion thereof even although pressure be exerted thereon. In addition to preventing the accidental slipping 110 or rolling off of the user in sleep from the spring S these auxiliary reinforcing springs 115

prevent sagging of the bed at the sides which often occurs by reason of persons sitting on the edge of the bed.

I claim as my invention:

5. In a bed spring, the combination of a frame composed of angle iron side bars, upstanding end members connecting said side bars with their upper ends disposed in a plane above the plane of the side bars, a woven wire fabric arranged between said ends and side bars, coiled springs connecting said fabric and the upper edges of said ends forming a housing below said fabric, a plurality of longitudinally aligned uniformly 10 compressible truncated cone-shaped spiral springs secured at one end to the side members of said frame, said springs being arranged in close proximity and alternately 15 with the base of one disposed downwardly

and the base of the next upwardly, all of 20 said springs being of the same height, the final coil in each spring which has its base extending upwardly being each bent into a longitudinally extending loop at the outer side of the spring which loops project above 25 the woven wire fabric to form mattress retaining means, and wire loops connecting one of the wires of the fabric at each side edge thereof with the upper ends of the spiral springs.

30

In testimony whereof I have hereunto set my hand in presence of two subscribing witnesses:

JOHN B. MARTIN.
